United States Patent Office

Des. 211,809
Patented July 30, 1968

211,809

TOY JEEP

Robert Genin, Scarsdale, N.Y., assignor to Child Guidance Toys Inc., Bronx, N.Y., a corporation of New York

Filed July 18, 1967, Ser. No. 7,865

Term of patent 14 years

(Cl. D34—15)

Fig. 1.

Fig. 2.

FIG. 3.

FIG. 4.

FIG. 1 is a perspective view of my design for a toy jeep whose body is transparent to reveal the inner gears thereof;

FIG. 2 is a plan view of the jeep;

FIG. 3 is a front view of the jeep; and

FIG. 4 is a rear view of the jeep.

I claim:

The ornamental design for a toy jeep, substantially as shown and described.
